UNITED STATES PATENT OFFICE.

JOSEPH H. GREENLEAF, OF NEW HAVEN, CONNECTICUT.

FARE-REGISTER.

SPECIFICATION forming part of Letters Patent No. 476,741, dated June 7, 1892.

Application filed May 25, 1891. Serial No. 393,967. (No model.)

To all whom it may concern:

Be it known that I, JOSEPH H. GREENLEAF, a citizen of the United States, residing at New Haven, in the county of New Haven and State 5 of Connecticut, have invented certain new and useful Improvements in Fare-Registers; and I do hereby declare the following to be a full, clear, and exact description of the invention, such as will enable others skilled in the art to 10 which it appertains to make and use the same.

This invention relates to certain novel and useful improvements in fare-registers for street-cars, stages, and other public vehicles; and the objects of my invention are, first, to 15 provide a machine having a novel form of indicating device capable of operation up to a certain given number and of indefinite repetition; second, in combination with such indicating mechanism additional registering 20 mechanism which shall not only tally with the detail addition of the indicating-wheels, but shall also preserve a strict account of the repetitions of the indicating mechanism which have occurred; third, to provide a novel 25 form of mechanism for this totalizing-register, and, fourth and in general, it is an object of my invention to provide a machine which shall be simple and compact in construction, positive in its operation, and not likely to get 30 out of order; and with these ends in view my invention consists in the construction and combinations of elements hereinafter fully explained, and then recited in the claims.

In order that such persons as are skilled in 35 the art to which this invention appertains may fully understand its construction and method of operation, I will describe the same in detail, reference being had to the accompanying drawings, which form a part of this specification, and in which—

Figure 1 is a front elevation of my machine; Fig. 2, an end elevation from the right hand of Fig. 1; Fig. 3, a front elevation with the case sectioned; Fig. 4, a section at the line $x-x$ of Fig. 3, certain internal parts being shown in end elevation; Fig. 5, a horizontal section on the line $y-y$ of Fig. 3; Fig. 6, a section on the line $z-z$ of Fig. 3; Fig. 7, a vertical section on the line $v-v$ of Fig. 3; Fig. 8, a vertical section on the line $w-w$ of Fig. 3; Fig. 9, a detail plan view of the stationary figure; Fig. 10, a

detail end elevation, substantially like Fig. 2, with the registering mechanism removed. This view is the actual size of the machine, preceding views having been reduced one-half. 55

Like numerals of reference denote the same parts in all the figures of the drawings.

The fare-register, which forms the subject-matter of this specification, is adapted to be fastened to the end or other convenient point 60 against the wall of the street-car or other vehicle in connection with which it is to be used. To this end the inclosing case 1 is provided with means of attachment, such as the perforated ears 2. This case has within it and 65 attached to the back thereof a base or frame 3, upon which the moving parts of the register are mounted.

4 represents a pair of standards projecting outward at right angles to the base, and in 70 these standards is journaled a horizontal shaft 5, which constitutes the main shaft of the machine.

6 is a units-indicating wheel fast upon and adapted to revolve with said shaft. Near its 75 outer end said wheel carries a ratchet-wheel 7, having ten teeth, and also a grooved wheel 8, around which extends a friction-band 9, having its ends secured to the frame. The contact of said band against the wheel is 80 rendered elastic by means of a spiral spring 10, interposed in the length of the band.

The outer end of the main shaft heretofore referred to bears a spur-pinion 11, whose function will be hereinafter explained. 85

12 is a bell-crank lever with its arms substantially at right angles. At its elbow it is fulcrumed about the main shaft 5.

One of the arms, which I denote by the numeral 13, carries a pivoted actuating-pawl 90 14, whose end engages the periphery of the ratchet-wheel 7 and is held in contact therewith by means of a spring 15. The other arm of said lever, denoted by 16, has pivoted thereto a draw-link 17, which projects outward through the case and is adapted for the attachment of the pull strap or cord in any desired manner. A stop 18, having two abutment-shoulders, limits the throw of the bell-crank lever by engagement with its arm 13. 95 Said bell-crank lever is spring-retracted by means of a spiral spring 19, whose ends are

connected, respectively, with the arm 16 of the bell-brank and a bracket 20, secured to the frame. Another bracket 21 projects upwardly from the frame and has pivoted thereto a retaining-pawl 22, held in engagement with the ratchet-wheel by means of a spring 23 and provided with a bell-hammer 24, which operates in connection with a bell 25, mounted upon the frame and adapted to ring at each registering action of the machine.

The operation of this part of my invention is as follows: By pulling the operating cord or strap the bell-crank lever will be vibrated about its center and the operating-pawl, whose end engages the face of one of the ratchet-teeth, will carry the ratchet and the units-indicating wheel one step, the abutment-stops permitting to the bell-crank sufficient movement for this purpose. As the ratchet-wheel moves forward the end of the retaining-pawl will ride upon the back of the tooth beneath it, and this movement will retract the hammer away from the bell 25. When the tooth has passed entirely beneath the retaining-pawl, the latter will be drawn downward over the face of the tooth by its spring, thereby preventing any retrograde movement of the ratchet-wheel and at the same time causing the bell-hammer to strike the bell. The spring 19 will carry the bell-crank lever back to its original position upon release of the strap, when it drops into engagement with the next tooth.

Upon its periphery the units-indicator wheel bears numerals from "0" to "9," and upon its left side (see Fig. 3) said wheel is provided with an extension 26, which is in the form of an outwardly-projecting metallic band, having openings therethrough, ten in number—one opposite to each of the units upon the main portion of the indicator-wheel. At its extreme left said extension is provided with a single narrow opening 27, whose purpose will be presently explained.

Journaled about the same shaft as the units-indicator wheel and in line with said wheel and with its periphery inside the extension of the units-wheel heretofore referred to, is a tens-indicator wheel 28, having its periphery numbered like the units-wheel. Its figures appear through the openings in the part 26. At the extreme left it is provided with an opening 29 in the same plane and adapted at certain times to register with the similar opening at the extreme left of the extension of the units-wheel. The purpose of this construction is to disclose at every hundred operations of the actuating-lever the figure "1," which is borne upon a fixed tablet 30, whose end projects inward beneath the peripheries of the units and tens wheel to a point in line with the two small openings just described. This tablet is carried upon the left-hand standard or is otherwise secured to the frame. The tens-wheel carries a friction-wheel 31, similar to the same parts on the units-wheel and engaged by a spring-tensioned friction-band 32.

The function of both these friction-bands is to prevent the wheels from overthrowing, and this is necessary when the initial movement 70 imparted to the bell-crank is particularly quick or severe. The tens-indicating wheel carries a ten-toothed ratchet-wheel 33, and the units-wheel upon its inner side carries a pivoted actuating-pawl, which projects laterally 75 outward, so as to lie in the same vertical plane as the ratchet-wheel 33. This pawl performs the carrying movement whereby one complete revolution of the units-wheel will actuate the tens-wheel one step. This pawl 35 is normally held out of engagement with the ratchet-wheel 33 by means of a spring 34, and therefore would be carried round said ratchet-wheel without moving it. It is thrown into engagement with and moves it one step at 80 each complete revolution of the units-wheel by means of a cam 36, which is affixed to the frame and engages a toe 37 upon the pawl in such manner as to throw the latter into engagement with the ratchet-wheel and retain 85 it in such engagement so long as the toe engages the surface of the cam. The length of the cam is sufficient to hold the pawl against the ratchet-wheel through one operation of the bell-crank, and as soon as the 90 toe passes out of engagement with the cam the spring throws the pawl out of contact with the ratchet-wheel, there to be retained until again brought into contact with the cam at the next revolution. The toe, as shown 95 at Fig. 4, projects through the periphery 100 of the units-indicating wheel just at one side of the face of the tens-wheel. The enclosing case is provided with openings A, 105 through which the figures on the indicating-wheels are seen, and also once in one hundred operations the figure "1" upon the tablet in conjunction with the two zero characters upon the indicating-wheels. This stationary 110 figure can only be seen when the two openings at the left hand of the indicating-wheels are in conjunction over this figure. Of course 115 this only occurs once in a hundred operations of the machine, because while the units-wheel opening is over the tablet once at each revolution and the opening in the tens-wheel once at each revolution the two will only be in conjunction with the tablet once in every ten revolutions of the units-wheel or once in each 120 hundred operations of the machine.

The parts heretofore described constitute an indicating mechanism capable of automatic operation up to one hundred when made with two wheels and the stationary digit above referred to and up to one thousand 125 when three wheels are employed and capable of repeating this indicating operation indefinitely. In connection with this indicating mechanism I use a registering mechanism, whereby not only is each operation of the machine up to one hundred duly reckoned, but each hundred is also reckoned up to ten thousand, and in this respect, also, indefinite repetition may be had. The parts of the machine 130

whereby this is effected are now to be described.

As has heretofore been described, the end of the main shaft bears a spur-pinion 11. This meshes with two gears 38 and 39, the former having one hundred and one teeth and the latter one hundred teeth. Both of these are upon a short shaft 40, whose bearing is in the top of a standard 41, projecting from the base. The gear 38, as shown at Fig. 7, is mounted upon said shaft in such manner as to carry the latter. The gear 39 is loose and revolves upon said shaft as an axis. The outer face of the gear 39 bears an annular dial 42, graduated into one hundred equal parts, as shown at Fig. 2. The face of said dial is recessed, as appears at Fig. 7, and within this recess and at the bottom thereof is contained a gear 43, whose hub is fastened to the shaft 40, and therefore revolves with the gear 38. Like said gear 38 it has one hundred and one teeth. Around the hub of this dial 42 and journaled thereon is a double part consisting of a gear 44, having one hundred teeth, and a pointer-plate 45, upon whose outer surface, as shown at Fig. 2, is a representation of a pointer which operates, in conjunction with the figures, upon the annular dial 42. The gear 39 carries within the recessed outer face, heretofore described, a spur-pinion 46, which engages with two gears 43 and 44. A fixed pointer 47, which is secured to one of the standards or other fixed portion of the machine, projects over the outside edge of the dial 42 and is adapted to indicate in connection therewith. For the sake of convenience said dial bears two sets of graduations, one adapted to operate in connection with the fixed pointer just referred to and the other in connection with the pointer on the plate 45. The pointer-plate is made in the form shown for the purpose of securing the internal gearing as against the entrance of dirt. Except for this function an ordinary pointer or dial-hand would answer every purpose.

The operation of this portion of my machine is as follows: As the pinion 11 is revolved by the shaft the two gears 38 and 39 are moved thereby one tooth at each operation of the bell-crank lever. As heretofore set forth, the gear 43 is carried with the gear 38, the gear 44 being journaled on the shaft. The one-hundred-toothed gear 39 being driven by the pinion 11, will impart to the annular dial one full turn in one hundred operations. This dial carries with it in its revolution the pinion 46, which, as before explained, meshes with both the gears 43 and 44. It is intended that the fixed pointer shall, in connection with the outer dial, indicate units from "1" to "100" and then repeat. It is intended that the finger or arrow on the pointer-plate shall indicate the rotations of the dial past the fixed pointer—that is, one step for each one hundred steps of the latter. This is accomplished by means of the gears 39 and 44,

which have teeth one hundred in number, and therefore equal to the index-spaces on each of the dials, and the gears 38 and 43, which are given each one more tooth than the gears 39 and 44 and the index-spaces on the dial, or one hundred and one. By this differential gearing, when the dial is rotated intermittently by the operation of the pinion to bring the numbered edge of said dial into the relation which it assumes to the fixed pointer and when the dial has made a complete revolution, then by reason of the one extra tooth in the gear 43, which is carried by the similar gear 38, and the intermeshing of the pinion 46 with said gears 43 and 44 the finger on the pointer-plate will, at the conclusion of the revolution of the dial-plate, be brought into line with the first index-line beyond the zero-point on such dial, and thus indicate the sum of such whole revolution or one point representing one full hundred. In other words, if the finger on the pointer-plate shall indicate "9" and said dial, in connection with the fixed pointer, shall indicate "50," then it is certain that said dial, has completed nine whole revolutions of one hundred points each, and fifty steps of the tenth revolution, or nine hundred and fifty operations in all.

I claim—

1. In a machine of the character described, the combination, with the main shaft bearing the units-indicating wheel, the latter provided with a tubular extension having openings therein, of the ratchet-wheel and pawl for the operation of the units-wheel step by step, the tens-indicating wheel journaled upon the main shaft within the extension of the units-wheel, a ratchet-and-pawl mechanism interposed between the units and tens wheels and adapted to impart a one-to-ten movement from the former to the latter, and a stationary figure-tablet within the extension of the units-wheel and beyond the edge of the tens-wheel, the whole arranged substantially as and for the purpose set forth.

2. In a fare-register, the combination, with the main shaft having attached thereto the units-indicating wheel, of the ratchet-wheel carried by the units-wheel and the pawl for the operation of said ratchet-wheel, a tubular perforated extension upon said units-indicating wheel, a tens-indicating wheel journaled upon the main shaft alongside the units-indicating-wheel and visible through the openings in the extension, a ratchet-wheel carried by said tens-indicating wheel, a pawl hinged within the units-indicating wheel with its face in line with the ratchet-wheel on the tens-wheel and having a toe projecting outwardly beyond the periphery of said units-wheel, a cam adapted to engage and depress said pawl once at each revolution, a pinion fast on the main shaft, and a pair of gears having an unequal number of teeth engaged and operated by said pinion, and indicating dials and pointers actuated by said gears, substantially as and for the purpose herein specified.

3. In a machine of the character described, the combination, with the main shaft, of the units-wheel carried thereon and means for operating the same step by step, a tubular extension upon said units-wheel, provided with ten openings in one plane and a single opening beyond the ten-openings, the tens-indicating wheel journaled upon the main shaft within the tubular extension and having itself an extension provided with a single opening in the same vertical plane with the single opening in the units-wheel extension, a ratchet-wheel carried by the tens-wheel, a pawl carried by the units-wheel and adapted to operate the ratchet on the tens-wheel, a fixed sign-bearing tablet in the same plane with the two single openings heretofore referred to, a pinion carried by the main shaft, and registering mechanism, substantially as described, engaged and driven by said pinion, for the purpose and in the manner hereinbefore described.
4. In a fare-register, the combination, with the inclosing casing, of the horizontal shaft bearing the indicating-wheels and means, as described, for operating said wheels, the pinion 11, fast upon said horizontal shaft at one end thereof, and the differential gears 38 and

39, and suitable connections between said gears and the dials, both of said gears engaged and driven by the pinion 11, substantially as and for the purpose set forth.

5. In a fare-register, the combination, with the horizontal main shaft having attached thereto the units-indicating wheel, of the tens-indicating wheel journaled on said shaft and actuated from the units-indicating wheel, the bell-crank lever and its connections whereby step-by-step movement is imparted to the units-indicating wheel, the pinion 11, borne upon the main shaft and partaking of its motion, the differential gears 38 and 39, journaled below the main shaft and engaged and driven by its pinion, and the dials and their connections with the gears 38 and 39, all of said parts combined and adapted to operate substantially as and for the purpose hereinbefore set forth.

In testimony whereof I affix my signature in presence of two witnesses.

JOSEPH II. GREENLEAF.
